(57) **CLAIM**

The ornamental design for a needle holder with exchangeable handles, as shown and described.

DESCRIPTION

FIG. 1 is a rear isometric view of a needle holder with exchangeable handles in accordance with the new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken line showing of the shaft area in FIGS. 1–6 is for the purpose of illustrating environmental structure and forms no part of the claimed design.

1 Claim, 5 Drawing Sheets

FIG. 3

FIG. 4

FIG. 5

FIG. 6

FIG. 7
